UNITED STATES PATENT OFFICE.

PERRY M. MOORE, OF OKLAHOMA, OKLAHOMA, ASSIGNOR OF ONE-HALF TO HULBERT S. CLARK AND FRANK E. FAIN, BOTH OF OKLAHOMA, OKLAHOMA.

ELASTIC PUPPET-VALVE.

1,238,175.

Specification of Letters Patent.

Patented Aug. 28, 1917.

Application filed April 9, 1917. Serial No. 160,763

To all whom it may concern:

Be it known that I, PERRY M. MOORE, a citizen of the United States, residing at Oklahoma City, in the county of Oklahoma and State of Oklahoma, have invented a new and useful Elastic Puppet-Valve, of which the following is a specification.

The subject of this invention is a puppet valve wherein a reciprocating valve and rotary cam are co-operatively associated, and the objects of the invention are, first, to lessen the load upon the cam shaft caused by the cam closing spring, second, to provide means for positively opening and closing the valve, third, to provide means for causing a sudden opening of the valve and a gradual closure, fourth, to provide shock absorbing means in the valve actuating mechanism, fifth, to provide means for positively seating the valve and resilient means for retaining the valve, when seated, on its seat, sixth, to provide resilient means for retaining a valve on its seat, and means for gradually releasing the resilient means and positively opening the valve, and seventh, to provide means for preventing the valve unseating on one side due to the actuating stem being out of alignment.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

One practical embodiment of the invention is shown in the accompanying drawing, wherein:

Fig. 1 is a side elevation, partly in section, of a valve and operative mechanism therefor, constructed in accordance with my invention.

Fig. 2 is a vertical cross section taken on the line 2—2 of Fig. 1.

Fig. 3 is a horizontal section on the line 3—3 of Fig. 1.

Fig. 4 is a horizontal section on the line 4—4 of Fig. 1.

Fig. 5 is a cross section of a modification of the cam construction.

Referring to the drawings by numerals:

55 The numeral 1 indicates the cylinder wall

of a motor having a passage 2 communicating with a port 6, which port is provided with a seat 5.

A valve 4 is adapted to the seat 5, and is formed with a valve stem 7. The end of the valve stem 7 is provided with a longitudinal bore 8, adapted to receive the end of a cam rod 9. The end of cam rod 9 fits loosely within the bore 8, as shown most clearly in Fig. 1, to permit play between the parts to compensate for slight variations from true alinement, and so prevent the valve from unseating at one side. The stem 7 is further provided, adjacent its inner end, with diametrically opposed, longitudinal slots 10, through each of which extends an end of a pin 11, which is mounted in a transverse bore formed in the rod 9, near the end thereof. The pin 11 has a sliding fit in the slots 10, and its extending ends rest within a cup washer 12, which is slidably mounted on the stem 7. Another cup washer 13 engages the washer 12 and is inverted to receive, within its cupped portion, one end of a coiled compression spring 14, which surrounds the stem 7 and has its other end seated in a cupped nut 15. The annular flange portion of the cup nut 15 is provided with an opening 16, to which is adapted the tongue of a lock washer 17.

As will be readily understood from the foregoing, a yielding connection is formed between the valve stem 7 and the cam rod 9, which permits the cam rod to move after the valve is seated. This movement of the cam rod with respect to the valve stem takes place after the seating of the valve and before the unseating thereof, and permits the valve to be seated without shock, as well as compensating for wear of the valve and seat. The outer end of the cam rod 9 is angled to form a stub shaft 18, upon which turns a roller 19.

A cam 20 is provided on a cam shaft 21, and secured to the cam shaft by means of a bolt 22 are two registering sections. Each of these sections comprises, a collar portion 23, adapted to engage the cam shaft 21 and to be secured thereto by the bolt 22; a back plate 24; and a flange section 25. When the two sections are in register, and clamped to the cam shaft, the inner faces of the flange 25 conform to the curve of the cam 20 and are associated therewith to form a cam groove. The stub shaft 18, with its roller 19,

extends within this groove. As will be seen most clearly from Figs. 1 and 2, the diameter of the roller 19 is slightly less than the width of the cam groove, so that the 5 roller never contacts the face of the cam 20 and the flange 25 at the same time. The purpose of this will be clear when the operation of the device is hereinafter described.

At an intermediate portion of the cam rod 10 9 is formed an enlargement 26, extending laterally to one side of the rod and adapted to slide within a guide 27, which guide is preferably in the form of a flattened cylinder, as shown most clearly in Fig. 3.

15 Fig. 5 illustrates a modification of the invention in which the cam 20' is formed integral with the back plate 24' and the collar is bolted to the shaft 21', in the manner shown in Fig. 1.

20 The operation is as follows:—Referring particularly to Fig. 2, the position shown is that of complete opening of the valve. Considering the cam to be turning in the direction indicated by the arrow, the valve 25 will start closing as soon as the position shown is passed, and will continue to close until the point 28 is reached, at which point the valve is seated.

As soon as the cam has passed the point 30 28, the roller 19 will cease to contact the cam 20, and will be engaged by the flange 25 and, from the point 28 to 29, compression of the spring 14 takes place, the valve remaining on its seat. From 29 to 30 no 35 movement of the cam rod takes place, the valve still remaining closed. From the point 30 to 31 the spring 14 is expanding, the valve still being held on its seat by the tension of the spring, and the roller 19 maintained in contact with the flange 25 by the 40 same means. At the point 31, the spring 14

has completely expanded and the roller 19 is disengaged by the flange 25 and again engaged by the cam 20, the valve opening from this point to the starting point. 45

It will be seen that the valve is gradually and carefully seated, without shock or jar. Because the roller 19 is not in contact with the flange 25 during the seating of the valve, no pull is exerted on the valve until it is 50 completely seated and then such pull is cushioned by the spring 14. A quick and positive opening of the valve is also obtained by retaining the roller 19 in contact with the flange 25 and out of contact with 55 the cam 20 until the point for admission is reached. This prevents any accidental opening, or leakage of the valve, due to irregularity of the cam surface.

Having described my invention, what I 60 claim as new and desire to secure by Letters Patent, is:—

A puppet valve, comprising a valve and its stem, a sleeve threaded on the stem, said sleeve provided with longitudinal slots, 65 washers sliding on the sleeve, a nut threaded on the free end of the sleeve, a coiled spring surrounding the sleeve and confined between the washers and the nut, a cam rod having one end sliding in the sleeve and 70 provided with an aperture, a pin passing through the aperture and the slots of the sleeve and resting on the uppermost washer, a shaft, and a cam on the shaft and operatively engaging the cam rod. 75

In testimony that I claim the foregoing as my own, I have hereto affixed my signature in the presence of two witnesses.

PERRY M. MOORE.
